It is certified that error appears in the above-identified patent and that said Letters Patent is hereby corrected as shown below:

The patent includes 12 drawings in its claim. This is erroneous.

There should only be 6 figures claimed in this design.

A copy of the Notice of Allowance, indicating the restriction of the design from 12 figures to 6 is attached. The enclosed paperwork clearly shows that Group II (Figures 7-12.) was cancelled in the Response to Restriction Requirement filed on May 12, 2008.

EXAMINER'S AMENDMENT

An examiner's amendment to the record appears below. Should the changes and/or additions be unacceptable to applicant, an amendment may be filed as provided by 37 CFR 1.312. To ensure consideration of such an amendment, it MUST be submitted no later than the payment of the issue fee.

Restriction Election

Group II and the accompanying figure descriptions have been withdrawn from further consideration by the examiner, 37 CFR 1.142(b), as being for the nonelected design. Election of Group I was made without traverse in the reply filed on 12 May 2008. Figures 7 through 12 are cancelled at the request of the applicant.

Drawings

1. Fig. 2 shows lines that overlap and appear solid black. This figure should be redrawn using a lighter, smooth, even line weight. All lines must be clean, clear and well defined (see 37 CFR 1.84(l)).

Specification

1. For clarity the title **has been amended** throughout the application, original oath/declaration excepted to read: **Handbag**
2. For clarity the preamble **has been amended** to read: **...design for HANDBAG, of which...**
3. For clarity the claim **has been amended** to read:
The ornamental design for a Handbag as shown and described.
4. The following statement must be used to describe the broken lines on the drawing (MPEP 1503.02, subsection III):
The broken line showing of rivets, zippers, zipper pulls, rectangular label, and straps is included for the purpose of showing environmental portions of the Handbag and forms no part of the claimed design.

Page 4 of 4

Application/Control Number: 29/289,282

Page 3

Art Unit: 2914

The above statement **has been inserted** in the specification preceding the claim.

Corrected drawing sheets in compliance with 37 CFR 1.121(d) are required in reply to the Office action to avoid abandonment of the application. Any amended replacement-drawing sheet should include all of the figures appearing on the immediate prior version of the sheet, even if only one figure is being amended. The figure or figure number of an amended drawing should not be labeled as "amended." If a drawing figure is to be canceled, the appropriate figure must be removed from the replacement sheet, and where necessary, the remaining figures must be renumbered and appropriate changes made to the brief description of the several views of the drawings for consistency. Additional replacement sheets may be necessary to show the renumbering of the remaining figures. Each drawing sheet submitted after the filing date of an application must be labeled in the top margin as either "Replacement Sheet" or "New Sheet" pursuant to 37 CFR 1.121(d).

When preparing new drawings in compliance with the requirement therefor, care must be exercised to avoid introduction of anything which could be construed to be new matter prohibited by 35 U.S.C. 132 and 37 CFR 1.121.

Any inquiry concerning this communication or earlier communications from the examiner should be directed to Kathleen M. Sims whose telephone number is 571-272-8706. The examiner can normally be reached on Monday through Friday from 8:30 AM to 5:00 PM. If attempts to reach the examiner by telephone are unsuccessful, the examiner's supervisor, T. Chase Nelson, can be reached on 571-272-2641. The fax phone number for the organization where this application or proceeding is assigned is 571-273-8300.
